UNITED STATES PATENT OFFICE.

GEORGE CAWTHON, OF REDWOOD CITY, CALIFORNIA, ASSIGNOR TO AXFORD AND DE SHIELDS, A COPARTNERSHIP COMPOSED OF H. W. AXFORD AND A. DE SHIELDS, BOTH OF SAN JOSE, CALIFORNIA.

DESIGN FOR A DOOR KNOCKER.

Application filed August 30, 1923. Serial No. 7,123. Term of patent 3½ years.

To all whom it may concern:

Be it known that I, GEORGE CAWTHON, a citizen of the United States, residing at Redwood City, in the county of San Mateo and State of California, have invented a new, original, and ornamental Design for Door Knockers, of which the following is a specification, reference being had to the accompanying drawing, forming part thereof.

In the drawing:

Figure 1 is a front elevation of a door knocker embodying my new design.

Figure 2 is a side elevation of the same.

The ornamentation consists, mainly, in a formal arrangement of the conventionalized California poppy.

I claim:

The ornamental design for a door knocker as shown.

GEORGE CAWTHON.
